UNITED STATES PATENT OFFICE.

LEWIS M. WALKER, OF CRANSTON, RHODE ISLAND.

MACHINES MAKING OR OPERATING UPON ELLIPTICAL OBJECTS.

Application filed November 10, 1921. Serial No. 514,843.

To all whom it may concern:

Be it known that I, LEWIS M. WALKER, a citizen of the United States, and a resident of Cranston, in the county of Providence and State of Rhode Island, have invented certain new and useful Improvements in Machines Making or Operating upon Elliptical Objects; and I do hereby declare the following to be a full, clear, and exact description of the invention, such as will enable others skilled in the art to which it appertains to make and use the same.

This invention relates to improvements in machines for making or operating upon elliptical forms,—one object of my present invention being to provide simple and efficient means which may be operated to mark or cut objects of elliptical shape or to grind or polish objects of such shape, and to so construct the machine that it may be adjusted to make or operate upon elliptical objects of different relative dimensions or of different sizes, and which may also be adapted to make or operate upon objects from a true circular shape to circles or ellipses of any desired size within the capacity of the machine.

With this and other objects in view, the invention consists in certain novel features of construction and combinations of parts as hereinafter pointed out and set forth in the claims.

In the accompanying drawings, Figure 1 is a view in elevation showing an embodiment of my invention; Figure 1^a is a view at right angles of Fig. 1; Figure 2 is a plan view of a portion of the mechanism; Figure 3 is a sectional view of the structure shown in Figure 2; Figures 4 to 11 are detail views; Figures 12 and 13 are views showing different tools and holding means therefor, and Figures 14, 15 and 16 are views showing devices for adjustably supporting the tool devices, when the device is used for large sized work.

A base member (which may be of wood or metal) is shown at 1, and to this a metal plate 2 is secured. The plate 2 supports a shaft 3 having a threaded shank 4 which passes through said plate and may terminate in a hole 4^a in the wooden base 1. A nut 4^b is screwed on the shank 4 and between said nut and the plate 2, a washer 5 is located,—the shaft 3 being thus rigidly se-

cured to the plate 2 and therefore to the base 1. A sleeve 6 having a flange or head 6^a is keyed to the shaft 3 and passes through an inner ball-bearing ring 7. Suitably spaced from this ring is an outer ball bearing ring 8 seated within a driving wheel 9,—which latter will preferably be made in the form of a sprocket wheel,—and anti-friction balls 10 are located between said rings 7 and 8. The head 3^a of the shaft may enter a hole in a driving plate 11. The head 6^a of the sleeve enters a suitable recess 6^c in the center of the driving plate and the latter is secured by screws 12 to the sprocket wheel. The driving plate 11 may be made elongated in form and is provided with a dovetailed guide 13 to enter a similarly shaped elongated guideway 14 in the under side of a circular guide plate 15. The guide plate 15 constitutes the lower member of a turning head 16, and is provided with an elongated opening 17 for the accommodation of the portion 3^a of the fixed shaft 3. The upper member of the turning head is formed by a circular plate 18 disposed above the plate 15 and held separated therefrom by posts 19 which may be secured in place by screws 20.

An elongated head 21 made rigid with the upper end of the fixed shaft 3, is disposed between the plates 15 and 18 of the turning head 16. This head is provided with an elongated dovetail guideway for the reception of a similarly shaped adjustable block 23 provided with an upwardly projecting pivot pin or post 23^a, on which a fulcrum plate 24 is pivotally mounted and enters an elongated guideway 25 on the under side of the top plate 18 of the turning head.

A wooden member 26 is located upon the top plate 18 and is held in place by means of dowel pins *a*, *b*, *b*, projecting upwardly from said top plate and entering sockets in the member 26,—said sockets being preferably reinforced by means of metal plates 27 secured to said wooden member. The dowel pins are arranged on a center line parallel with the center line of the drive plate 11 and at right angles to the guideway 25 in the top plate 18.

A wooden work-table 28 is located upon the member 26 and may be secured thereto. The work may be placed upon the table 28, or the latter may be provided with an open-

ing 28^a, so that a work holder of any desired construction may be mounted upon the wooden member 26. The top plate 18 of the turning head may be connected with the member 26 and work table 28, by means of arms 29 secured to the plate 18 by means of screws 30 and to the member 26 by means of thumb screws 31.

With the construction and arrangement of parts above described, it will be observed that when the fulcrum plate 24 is adjusted so as to be at one side of a line passing axially through the shaft 3 and through the center of the driving plate 11, and the sprocket wheel is turned, the turning head will rotate with it and by reason of the fact that the guide in the top plate 18 in which the fulcrum plate 24 is located, is disposed at right angles to the sliding connection of the lower plate 15 with the driving plate, the turning head and the work table carried thereby will be caused to turn in an elliptical path so that a tool or marker engaging the work will cut or mark an ellipse,—viz, form an elliptical figure.

By adjusting the fulcrum plate 24 relatively to the head 21, the relative dimensions of the elliptical path of the turning head may be varied, and by so locating said fulcrum plate that its center shall be in axial alignment with the fixed shaft 3, the path of the turning head and the work will be circular.

In the drawing, I have shown manually operable means for driving the sprocket wheel 9, but if desired, power means may be employed. In constructing the manually operable means, I provide on the base 1, a post 32 adjustably connected with said base by means of an adjusting screw 33 and on this post, a sprocket wheel 34 is mounted and provided with a crank or handle 35 for turning it,—motion being imparted from said sprocket wheel 34 to the sprocket wheel 9 by means of a drive chain 36.

The sizes of the figures to be made on or with the work supported on and moved by the turning head may be varied and the tool or marker controlled by means of the mechanism now to be described.

Mounted upon the base 1 at a suitable distance from the turning head and its operating mechanism, is a support 37, upon which a block 38 is hinged as at 39. A slotted arm 40 is disposed over the hinged block 38 and adapted to rest and to be moved over a guide plate 41 secured upon said block, said plate being provided with a flanged guide-rail 42 to enter a similarly shaped groove 43 in said arm. An angle bracket 44 is adjustably secured to one end of the arm 40 and to the upright member of said bracket, a tubular holder 45 for a tool 50 is secured, said tool being secured to the holder by a thumb screw 51. The tool 50 may be a marker, a

glass or other cutter, or a grinding or a polishing tool, but in Figure 1 of the drawing, it is represented as a pencil.

The tool 50 may be pressed to its work by the action of a spring 52, one end of which may be connected with a hook 53 projecting from the block 38 and the other end of said spring may be connected with a hook 54 on the base 1. To regulate the pressure of the tool on the work or to accommodate the tool to the thickness of the work, provision is made to adjust the tension of the spring. This may be accomplished by means of a manually operable screw 55 passing through a threaded hole in a block 56 secured to the bracket 38 and engaging a block 57 secured to the support 37.

The tool carrying arm 40 is adjustable longitudinally to adjust the tool relatively to the work and thus determine the size of the object to be made. To hold the tool carrying bar rigidly at any desired adjustment, a screw post 58 is made rigid with the plate 41 and passes upwardly through the slot in the arm 40, a manually operable clamping sleeve 59 being threaded on the post 58 and adapted to clamp said arm, a washer 60 being located between the sleeve 59 and said arm 40. To accomplish accurate adjustment of the tool carrying arm 40, a graduated strip 61 may be secured to said arm (with graduations on both its side and upper edge), and the graduations of this strip may be made to register with a gage line 62 on the plate 41.

The tool holding arm 40 may also carry a stop plate 61^a to engage the clamping sleeve 59, said stop plate having an elongated slot 62^a for the passage of screws 63, whereby it may be adjusted and one end of said plate may be provided with a lip 64 to overlie the washer 60.

Instead of employing a pencil as the tool, I may use other forms of tools for marking, cutting or grinding purposes. In Figure 12, is shown an adjustable tool holder for a pen 65. In this construction, an angle bracket 66 is adjustably secured to the arm 40, and to the vertical arm of this bracket, a vertically adjustable bar 67 is secured by a thumb nut 68. To the upper end portion of the bar, the arm 69 of the pen 65 is secured by a thumb screw 70.

In Figure 13, a bracket 71 is adjustably secured to the arm 40 and supports a glass cutter 72 and to the top of said bracket, a knob 73 is secured whereby pressure may be applied to the glass cutter.

When the device is to be used for large sized work which would require greater adjustment than can be obtained with the construction previously described, I may mount the support 37 adjustably upon the base 1. This may be accomplished by securing a frame 74 to the base 1, said frame being

provided with guides 75 to enter slots 76 in a frame 77 on which the support 37 is mounted,—the frame 77 and support 37 thereon, being secured at any desired adjustment by means of clamping devices 78.

Having fully described my invention what I claim as new and desire to secure by Letters-Patent, is:—

1. In mechanism of the character described, the combination with a rigid shaft, a driving wheel mounted thereon and a driving plate secured to the driving wheel, of a turning head comprising upper and lower plates spaced apart and secured together, the lower plate of said turning head having sliding connection with said driving plate, the upper plate of said turning head having a guideway on its under side disposed at right angles to the sliding connection between the lower plate and the driving plate, a rigid head on the rigid shaft and disposed between the plates of the turning head, a pivot member adjustably supported by said head, a fulcrum member mounted on the pivot member and movable in the guideway of the upper plate of the turning head, a support for work holding means mounted on said turning head, and tool holding means having a part disposed in a plane over the work supporting means.

2. In mechanism of the character described, the combination with a fixed shaft, driving means thereon and a driving member secured to said driving means, of a turning head having sliding connection with said driving member, said turning head having a guideway at right angles to the sliding connection between said turning head and driving member, an adjustable fulcrum member carried by said shaft and disposed in said guideway, dowels on said turning head, a supporting member mounted on the turning head and having sockets to receive said dowels, a work table on said supporting member, means connecting said supporting member and work table, and adjustable tool holding means having a part disposed in a plane over the work table.

3. In mechanism of the character described, the combination with a turning head and means for turning the same, of a support, a hinged member thereon, a tool carrying arm adjustable longitudinally on said member, a tool holder carried by said arm and adapted to be disposed at right angles to said turning head, a spring connected with said hinged member and the support and operable to press a tool in said holder against the work supported by said turning head, and means for adjusting the tension of said spring.

4. In mechanism of the character described, the combination with a turning head and means for turning the same, of a support, a hinged member thereon, a tool carry-

ing arm adjustable longitudinally on said member, a tool holder carried by said arm and adapted to be disposed at approximately right angles to said turning head, a spring connected with said hinged member and with the support and operable to press a tool in said holder against the work supported by said turning head, and means for adjusting said hinged member to vary the tension of the spring and regulate the pressure of the tool relatively to the work.

5. In mechanism of the character described, the combination with a turning head and means for turning the same, of a support, a hinged member thereon, a tool carrying arm adjustable longitudinally on said member, a tool holder carried by said arm and adapted to be disposed at right angles to said turning head, a spring connected with said hinged member and with said support and operable to press a tool in said holder against the work carried by said turning head, a part projecting from the hinged member and having a hole, a screw threaded through said hole to engage the support whereby the tension of the spring and hence the pressure of the tool relatively to the work may be adjusted.

6. In mechanism of the character described, the combination with a turning head adapted to support work to be operated upon, and means for turning said head, of a support, a member hinged to said support, a longitudinally adjustable slotted arm, guiding means on said hinged member for said arm, a screw projecting upwardly from said guiding means and passing through the slot in the arm, a clamping device threaded on said screw and adapted to engage said arm to hold the same at any desired adjustment, a tool holder carried by said arm and disposed at approximately right angles to the work on the turning head, a spring connected with said hinged member and operable to apply pressure to the tool carried by said tool holder, means for limiting the outward movement of said arm and the tool holder and tool, and graduated means for determining the accurate adjustment of said arm and the tool holder and tool carried thereby.

7. In mechanism of the character described, the combination with a turning head and means for causing said head and work carried thereby to move in an elliptical path, of driving means for said turning head comprising a wheel for driving the turning head, a second wheel, a driving connection between said wheels, and manually operable means connected with said second wheel.

8. In mechanism of the character described, the combination with a base, of a shaft fixed thereto, a turning head, a sprocket wheel for the driving head mounted

on said shaft, means for causing said turning head to move in an elliptical path, a second sprocket wheel adjustably mounted on said base, a chain connecting said sprocket wheels, and means whereby power may be applied to said second sprocket wheel.

9. In mechanism of the character described, the combination with a base, a turning head mounted on said base and adapted to support work, and means for driving said turning head, of a tool carrying arm disposed over the turning head, a tool holder carried by said arm, a support for said arm mounted on said base, means for securing said arm at any desired longitudinal adjustment, and an adjustable stop on said arm and cooperable with a part on said support to limit the movement of the arm in the direction from the support.

10. In mechanism of the character described, the combination with a base, a turning head mounted on said base and adapted to support work, and means for driving said turning head, of a tool carrying arm disposed over the turning head, a tool holder carried by said arm, a support for said arm, means for securing said arm at any desired longitudinal adjustment on said support and means for securing the support in a set position longitudinally of said base. 20
